WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK

DRY-CELL-SEALING DEVICE

Application filed March 9, 1925. Serial No. 14,145.

This invention relates to dry cells, and more particularly to new and useful improvements in the sealing of dry cells.

In dry batteries of the Le Clanche type it is desirable, as well known, to provide between the depolarizing mix or bobbin and the upper seal, which is usually of pitch, a free space for the gases evolved during the operation of the battery. Otherwise the pressure generated by the gases may burst open the container or the cell and cause the water contained in the mix rapidly to evaporate. Various arrangements have been suggested for this purpose, the simplest of which consists in the provision of a disc of paper or other insulating material provided at a certain distance from the top of the depolarizing mass. In such structures, however, it often happens that after the seal cools and the cell is subjected to more or less severe handling, the relatively heavy seal will settle and force the paper disc flush against the top of the depolarizing agglomerate. This will, of course, destroy the desirable air space. In order to avoid this it has been suggested so to arrange the paper disc, which is made of corrugated cardboard, that it rests normally on top of the depolarizing mass and provides in its interstices or convolutions the necessary air space. The objection to such arrangement is that the paper structure may be crushed by the seal, and that its construction and insertion into the battery can is relatively expensive.

In order to overcome these difficulties, in accordance with the present invention the seal of pitch or the like is anchored in the top of the battery can in a manner to prevent its settling and destroying the gas chamber. This is accomplished by providing a disc of paper or other insulating material at a certain distance from the top of the depolarizing mass. The paper is held in position merely by friction with the walls of the zinc can. The hot sealing material is poured on top of this paper disc and in order to prevent the displacement of this seal upon cooling, projections are provided in the zinc can which will permanently anchor it. It is important that the anchoring

means do not interfere with the assembly of the battery and particularly with the insertion or tamping of the depolarizing mixture. I have found that two or three slight indentations near the top of the zinc can will serve as a sufficient anchor without interfering with the assembling operation in any respect.

The drawing illustrates an embodiment of the invention in a dry cell shown partly in cross section.

The dry cell is of the usual type in which a zinc electrode 1 surrounds a centrally located carbon electrode 2, the space between these electrodes being filled with a mass of depolarizing material 3 which is separated from the zinc electrode by means of a lining 4 of paper or the like. After the insertion of the depolarizing bobbin 3 or the tamping down of the depolarizing mass in the container, the end of the paper lining 4 is folded down on top of the depolarizing mass as indicated at 5. A disc of paper 6 of a sufficiently large diameter to insure its frictional engagement with the zinc can 1 is inserted, but a space 7 is preserved between the top of the depolarizing mass and the paper disc 6. Near the top of the zinc can 1 two or more indentations 8 are made in the can and these indentations serve as an anchor for holding in place the pitch seal 9 which is poured hot into the container on top of disc 6.

What I claim is:

1. In a dry cell, a zinc container electrode, a carbon electrode centrally located therein, depolarizing mass partly filling the annular space in said container, a disc of insulating material frictionally held at a certain distance from the top of said container, spaced indentations in the zinc container above said disc, and a seal filling the space within the container above said disc.

2. In a dry cell, a zinc container electrode, a carbon electrode centrally located therein, depolarizing mass partly filling the annular space in said container, a disc of insulating material frictionally held at a certain distance from the top of said container, spaced indentations in the zinc container above said

disc, said indentations being sufficiently small to allow insertion of the liner without distortion, and a seal filling the space within the container above said disc.

5 In testimony whereof, I have signed my name to this specification this 2nd day of March, 1925.

WILLIAM F. HENDRY.
